UNITED STATES PATENT OFFICE.

JAMES W. ABERNETHY, OF ATLANTA, MISSISSIPPI.

ELEVATED RAILWAY.

No. 801,832.

Specification of Letters Patent.

Patented Oct. 17, 1905.

Application filed November 10, 1904. Serial No. 232,241.

To all whom it may concern:

Be it known that I, JAMES W. ABERNETHY, a citizen of the United States, residing at Atlanta, in the county of Chickasaw and State of Mississippi, have invented new and useful Improvements in Elevated Railways, of which the following is a specification.

The invention relates to an improvement in elevated railways, and specifically to a single-rail elevated railway.

The main object of the invention is to provide a road-bed of particular construction and to arrange in coöperation therewith a suitable conveyance to be supported by the single-rail 15 of the road-bed.

The invention is illustrated in detail in the accompanying drawings, in which—

Figure 1 is a plan view illustrating the road-bed and the locomotive structure. Fig. 2 is 20 a longitudinal section of the same. Fig. 3 is a transverse section of the same. Fig. 4 is a transverse section through the cab, showing the means for increasing the traction of the locomotive. Fig. 5 is a front elevation of the 25 locomotive. Fig. 6 is a longitudinal section through one of the boilers and the fire-box. Fig. 7 is a view in elevation illustrating the traction-adjusting means for the locomotive. Fig. 8 is a perspective illustrating a passenger-coach for my improved railway. Fig. 9 30 is a transverse section through the same. Fig. 10 is an enlarged elevation showing the ball-bearing connections for the main-track wheel. Fig. 11 is a sectional view of a roller-bearing which may be used in connection with 35 any part of the engine.

Referring to the drawings, it will be noted that my improved road-bed comprises a trestle-work or series of upright inclined frame-bars 1, suitably braced by cross-bars 2, forming 40 a road-bed of triangular shape in section. Secured to the meeting ends of the upright bars is the main track 3, which may be of any desired shape and size, though preferably a 45 flat rail, as illustrated. The guiding-tracks 4—one on each side of the frame and preferably in alinement with the brace-bar 2—are practically of usual construction, comprising a base 5, web 6, and tread 7. To provide, 50 however, for the exact bearing-surface between the guide-rail and its coacting wheel, the surface of the base 5 is inclined toward the framework, the specific line of incline being acquired by arranging the tread-surfaces 55 at right angles to the direction of pressure from said coacting wheels. This incline may

be readily determined by striking an arc through the longitudinal center of the guiding-wheels, with the main track as a center, and inclining the tread-surface at right angles 60 to a line tangential to said arc at the center of the wheel. This construction provides a road-bed of triangular shape, the apex of which furnishes the main or supporting rail for the operation of the conveyance, the guide-rails being positioned opposite each other in horizontal direction, whereby the pressure exerted on one guide-wheel will be resisted by the pressure exerted on the other.

To coöperate with the road-bed, I provide 70 a locomotive of particular construction having the usual cab and suitably-connected passenger-coaches, the structure of which parts may be readily seen from the drawings. The locomotive comprises duplicate boilers 8, smoke-stacks 9, pressure-cylinders 10, steam-domes 75 11, fire-boxes 12, one set of each of the parts being suspended on each side of the main rail 3. The engine is preferably supported by main wheels 13, flanged on opposite edges to 80 guide the wheel on the rail. The axle 14 of each wheel is provided on each side of the wheel with a crank 15, and the wheel is driven by circular driving rods or wheels 16, having radially-projecting ears 17, coupled directly 85 to the cranks 15, it being understood that a driving-wheel 16 is arranged on each side of the main track and is coupled to the cranks on the same side of both the forward and rear main wheels 13. An ear 18, projecting upward from each of the driving-wheels 16, is coupled to a crank 19 in the transverse crank-rod 20, the said cranks being suitably connected to the piston-rods 21, leading to the steam-cylinders 10. The cranks 15 on opposite sides of the wheels 13 are arranged in reverse direction to provide for the continuous driving through the operation of the driving-wheel 16 and to prevent centering of the cranks.

22 represents the usual valve-chests, fed by pipes 23 from the steam-domes 11, the valves in which are suitably controlled through valve-rods 24, connected to eccentrics 25, mounted on or driven by the transverse driving-rod 20. The admission of steam to the valve-chests is suitably controlled by the usual throttle-valve actuated through the usual lever 26, arranged in the cab 27.

To provide for added heating capacity of 110 the fire-boxes with relation to the boiler, I form an arcuate recess 28 in the base of the

boiler-cylinder to provide a channel underlying the flues, as clearly seen in Fig. 3. The channel so formed is in open communication with the fire-box 12 and with the smoke-box 29, whereby a portion of the heat from the fire-box will be directed through said channel, and by means of the comparatively large surface exposed therein the water in the boiler will be more readily heated and maintained at steam temperature.

The cab 27 of the locomotive, which may be of the usual type in so far as its general appointments are concerned, is supported upon main wheels 30, the axles 31 of which wheels 15 are preferably supported in bearings 32, fixed in the main frame of the cab. I prefer to construct the floor-frame of the cab to provide floors 33 on each side of a central inverted U-shaped portion 34, within which portion 20 34 the main wheels 30 are mounted. By this construction I provide for effectively guarding the main wheels and at the same time bring the floors 33 on the approximate level of the main wheel and rail to render the structure more stable in operation.

The guiding-wheels 35 are separated from the locomotive and arranged to bear one on each guide-rail 4, whereby to prevent undue sway of the locomotive when in operation.

The guide-wheels 36 of the cab are arranged 30 for adjustable contact with the guide-rails 4, whereby to vary the traction of the locomotive when ascending or descending grades, as will be understood. To provide for this adjustment, I support the guide-wheels 36 at the ends of rods 37 and connect the latter by links 38 with the frame-bar 39, fixed in the cab, the upper ends of the rods 37 being connected by a longitudinal bar 40. A lever 41, 40 arranged for locking engagement with the usual notched segment 42, is connected to the bar 40. It is evident that by suitable operation of the lever 41 the wheels 36 may be caused to bear with more or less pressure 45 upon the guide-rails 4 to increase or decrease the tractive power of the locomotive. I prefer to form the rods 37 in two sections, telescopically connected, and interpose a spring 43 between them, whereby to permit adjustment 50 of the parts under spring-pressure to accommodate the operation to various inequalities of the track.

It is to be understood that there is a guide-adjusting mechanism on each side of the cab, 55 whereby to permit varying adjustment on opposite sides, if desired, and that by preference the frame 39 for supporting the adjusting mechanism is made in a single piece, centrally following the U-shaped section 34 60 of the cab-floor and projecting below the same and bent upward to support the adjusting mechanism described. By this construction the cab is effectively braced at the parts subjected to strain.

The coaches designed for use with my im-

proved elevated railway are illustrated particularly in Figs. 8 and 9, wherein 44 represents a box-like structure, closed at the bottom by a floor 45, which floor is formed with a central triangular portion, comprising walls 70 46, to overlie the main track 3. The walls 46 are extended vertically above the track to provide a brace 47, reaching to the car-roof 48 and being there connected to a longitudinal stringer 49. Braces or struts 50 lead 75 from the stringer 49 to the junction of the floor with the side walls to brace the parts. The car is provided with the usual doors 52, opening on the side or at the ends, for the use of which latter steps 53 are provided. 80 The car is supported by main wheels 54, flanged to embrace the main track 3 and provided with a vertical stub 55, grooved to receive a series of balls 56; a second stub or shaft 57 being similarly grooved to receive 85 the balls 56. The upper end of the stub 57 is connected to the lower end of the braces 47, whereby the stubs 55 and 57 depend between the inclined walls 46, with the wheel 54 resting upon the rail 3, as will be understood. 90 Chains 58, or other flexible connectors, are secured to the stubs 55 and 57 to prevent accidental displacement of the parts. By this provision the car is practically supported upon a ball-bearing, which is yieldable in all directions to accommodate the movement of the car to the irregularities of the track without unnecessary jarring of the car, and at the same time facilitate the traveling of the car around the curve. The side walls 50 of the car depend 100 below the floor 45 and are arranged to support housings 59, in which a bearing 60 is movably mounted, being guided by a rod 61, connected to the bearing and projecting through an opening in the end wall of the 105 housing, a spring 62 encircling said rod and tending to maintain the bearing at its limit of movement toward the road-bed. The bearing 60 carries wheels 63, arranged to bear upon the tread of the guide-rails 4. The wheels 63 110 are flanged at 64 on their lower surfaces to engage the lower edge of the tread and prevent undue upward movement of the car.

It will be noted that I have provided an elevated railway in which the road-bed is of triangular shape in sections, carrying at its apex the main single rail 3. The locomotive and coaches are separated and combined with said rail is a guide-rail on each side of the road-bed designed to receive guide-wheels carried by 120 the moving parts. The resultant structure is very stable in operation, owing to the described distribution of the weight in connection with the means for preventing undue swaying of the locomotive or coaches, and 125 tends to ease and smoothness in operation heretofore impossible in structures of this character.

The means described for adjusting the tractive power of the locomotive permits the op- 130

erator to adjust in accordance with relation to the grade, permitting a utilization of practically all the power developed by the locomotive.

- 5 In Fig. 11 of the drawings I have disclosed a roller-bearing in which any of the axles, shafts, or rotary members of the engine may be journaled, and it comprises a head 65, having a passage extending therethrough, said 10 passage being enlarged at its ends to provide for the reception of roller-bearings 66. The roller-bearings are retained in applied position by means of caps 67, removably secured to the head.
- 15 Having thus described the invention, what is claimed as new, and desired to be secured by Letters Patent, is—
1. In an elevated railway, a single rail, a locomotive comprising duplicate parts suspended 20 on opposite sides of said rail, guide-rails arranged below said main rail, guide-wheels carried by the locomotive and bearing on said guide-rails, and means to adjust the contact of said guide-wheels and 18 ls.
- 25 2. In an elevated railway, a single rail, a locomotive comprising duplicate parts suspended on opposite sides of said rail, guide-rails arranged below said main rail, guide-wheels car-

ried by the locomotive and bearing on said guide-rails, and manually-operable means to 30 adjust the contact of said guide-wheels and rails.

3. In an elevated railway, a single rail, a locomotive comprising duplicate parts arranged on opposite sides of said rail, main wheels carried by the locomotive, and driving-wheels 35 connected with the steam-cylinder of the locomotive and with said main wheels.

4. In an elevated railway, a plurality of guide-rails arranged below the main rail, a 40 locomotive supported on said main rail and guide-rails, and means for coöperating with the guide-rails to adjust tractive power of the locomotive.

5. In an elevated railway, a single rail, a plurality of guide-rails arranged below the main rail, a locomotive supported on said main rail and guide-rail, and manually-operable means for coöperating with the guide-rails to adjust tractive power of the locomotive. 45

In testimony whereof, I affix my signature in presence of two witnesses.

JAMES W. ABERNETHY.
